UNITED STATES PATENT OFFICE.

WILBUR L. WRIGHT, OF FULTON, NEW YORK, ASSIGNOR TO OSWEGO FALLS CORPORATION, OF FULTON, NEW YORK, A CORPORATION OF NEW YORK.

CLOSURE DISK.

Application filed November 14, 1923. Serial No. 674,644.

To all whom it may concern:

Be it known that I, WILBUR L. WRIGHT, a citizen of the United States of America, and resident of Fulton, county of Oswego, 5 State of New York, have invented certain new and useful Improvements in and Relating to Closure Disks, of which the following is a specification.

This invention relates to closure disks incised at the top surfaces to outline portions that can be partially split or stripped from the tops of the disks and bent up to form relatively thin lift or pull tabs for extracting the disks from the mouths of containers 10 sealed thereby; and the objects and nature of the invention will be readily understood by those skilled in the art in the light of the following explanations of the accompanying drawings that illustrate what I now believe to be the preferred mechanical expression or embodiment of my invention from among other forms and arrangements within the spirit and scope thereof.

An object of the invention is to provide a 15 closure disk that can be applied to closure mouths by capping machinery, that can be imprinted on its top face, that can be economically produced in large quantities by machinery, and wherein the top surface of 20 the disk is so formed that a portion thereof can be utilized to form a double end or double thickness lift usually arranged at the center of the disk, the disk being composed of paper or other material suitable for the purpose 25 and from the top side of which, when suitably incised, relatively thin plies or tabs can be partially stripped or split and bent up to 30 form extracting lift or pull tabs.

With this and other objects in view, my 35 invention consists in certain novel features and in constructions and formations as more fully and particularly set forth and specified hereinafter.

Referring to the accompanying drawings, 40 forming a part hereof:

Fig. 1 shows a closure disk in accordance with my invention, in top plan on a somewhat enlarged scale.

Fig. 2 is a similar view showing the incisions continuous under the staple.

Fig. 3 is a section on the line 3—3, Fig. 1, dotted lines showing the central double lift as when split from the body of the cap and bent up to cap extracting position.

Fig. 4 is a section on the line 4—4, Fig. 2. 55

The closure disk 1, is flat and more or less stiff and elastic and is designed to snap into the mouth of a container, usually having an internal sealing shoulder, to seat on such shoulder to seal the container mouth. 60 Closure disks of this general type are usually known commercially as milk bottle or jar caps, and are composed generally of so-called pulp board or paper material that possesses the peculiar quality of readily 65 stripping, splitting or separating into plies or layers under certain conditions and manipulations. This peculiarity has been taken advantage of in forming such disks, to provide portions thereof that can be bent up to 70 serve as pull tabs for use in extracting the disks from the container mouths. However, to the best of my knowledge and information, such disks having tab forming portions integral therewith, have always provided single end or single ply tab portions 75 that when elevated to lift or extracting position were connected at their bases into the edge or peripheral portions of the disks.

I find that under some conditions and 80 for certain purposes, it is desirable to provide a paper material closure disk with portions integral therewith and capable of being split therefrom and bent up to form a double end or two ply lift rising from and 85 connected or coupled to the center of the disk top and composed of two free end tab portions, each relatively thin and in thickness but a minor fraction of the thickness of the disk, leaving the disk without openings 90 therethrough and of almost full strength and thickness throughout.

In the particular example shown, the top of the paper material-disk is incised by two relatively shallow approximately U-shape 95 or approximately encircling cuts 2, longitudinally aligned with each other diametrically of the disk top and meeting, or approximately meeting, at the center of the disk, to outline on the top race of the disk, an ap- 100

proximately straight elongated panel 2 at its opposite ends terminating short of and spaced from the diametrically opposite edge portions of the disk and at the approximate 5 center of its length crossing the approximate center of the disk. The disk is usually compressed at its top side, at 3, to form top depressions, immediately beyond the extremities of the panel 4, exposing the so-called 10 pick-up vertical end edges 4^a, of said panel to enable the same to be picked up at its opposite ends, i. e., to enable the operator by the use of his finger nail to initiate the splitting operation by lifting the opposite free 15 ends of the panel 4.

At the center of the disk, a wire staple 5, is located, with its straight top length elongated with respect to the width of the panel and arranged transversely across the top surface thereof and projecting beyond the panel 20 in opposite directions so as to straddle the panel about at the center of the length thereof. This staple is driven down through the disk outside of the panel and beyond the cuts 25 and the ends of the staple are turned up or clinched at the under surface of the disk. The staple is usually pressed into the surfaces of the disk to avoid the formation of objectionable projections at the disk 30 surfaces. The staple as shown in the drawings is somewhat exaggerated as to size and projection.

The disk making machine usually imprints the top faces of the disks with the desired indicia, applies and clinches the staples, by suitable blades and punches, incises, or produces the panel outlining cuts and the 35 depressions 3 in the top surfaces of the disks, and cuts out the disks from the paper material web or sheet.

The completed disks go on the market flat and smooth at their top and bottom faces (except for any unobjectionable projection of the staple) with the panel 4 flat and included in the body of the disk as shown in 40 Figs. 1, 2, and by full lines in Fig. 3, not being split or separated even in part from the body of the disk, whereby the disks can be used in the filling and capping machinery of commerce. The vertical cut 2 extends 45 down through the top surface of the disk and enters the body of the disk but a slight distance, usually to a depth equal to much less than one half the thickness of the disk, so that when the panel is split from the disk 50 to its central portion, first from one end of the panel and then from the other end, two free end approximately very thin tabs can be bent up to form the double end central 55 lift or twin pull tabs 6, indicated by dotted lines Fig. 3. A thin top ply of the paper material will split from the body of the disk, leaving the disk strong and imperforate, when the panel ends are stripped from 60 the disk and bent up, and the panel may or 65

may not then completely strip from the body of the disk up to the straddling staple. The staple prevents the separation of the center of the panel from the disk, which would otherwise occur, before or during the disk 70 extracting pull on the double end tab 6. By the location of the straddling staple or equivalent means across the center of the panel, the tabs formed by the panel are strengthened and prevented from completely 75 separating from the disk, and by this arrangement either or both panel ends can be stripped and bent up to serve as a pull tab where the ply split from the disk is of sufficient strength to enable one panel end to 80 serve as a pull tab. In the structure shown by Fig. 1, the incision formed by cuts 2 is not continued across the top surface of the disk covered by the staple but said cuts stop short of the staple. 85

Fig. 2 shows the incision formed by cuts 2^a, continuous under the staple, in which even the incision is made before the staple is applied.

It is evident that various variations might 90 be resorted to without departing from the spirit and scope of my invention and hence I do not wish to limit myself to the exact disclosures hereof.

What I claim is:

1. A paper material closure disk, of the character substantially as described, without projections at its top and bottom faces, preventing its use in container capping machinery, said disk having its top face incised 100 within the boundaries thereof by a shallow cut forming an elongated panel formed to be split upwardly from the upper part of the disk from both ends toward the center of the panel to form a thin double end lift, the disk being provided with means traversing the top face of the central portion of the panel and extending beyond the same to bind the double end lift to the disk and transmit the extracting pull of the double lift to the 105 disk.

2. A paper material closure disk having its top face incised within the boundaries thereof by a shallow cut forming an elongated panel formed to be split upwardly 110 from the upper part of the disk from both ends toward the center of the panel to form a double end lift, means being provided to prevent the center of the panel splitting from the body of the disk.

3. An imperforate paper material closure disk incised at its top face to form an elongated panel, the center of the length of which is located approximately at the center of the disk, and a staple secured to the disk and transversely straddling said panel intermediate its length, said panel formed to split upwardly from the body of the disk as a thin ply from either end toward the 115 staple to form a double end lift tab.

4. A paper material closure disk having its top face incised within the boundaries thereof by a shallow cut forming an elongated panel formed to be split upwardly from the upper part of the disk from both ends toward the center of the panel to form a double end lift, and a staple driven

through and clinched to the disk and traversing the top face of the panel midway its length.

In testimony whereof I have hereunto set my hand at Fulton, N. Y., this 12th day of November, 1923.

WILBUR L. WRIGHT.
